UNITED STATES PATENT OFFICE

126,490

DESIGN FOR A PIN CLIP

Gene Verrecchio, Providence, R. I., assignor to
Cohn & Rosenberger Inc., New York, N. Y., a
corporation of New York

Application March 3, 1941, Serial No. 99,316

Term of patent 3½ years

To all whom it may concern:

Be it known that I, Gene Verrecchio, a citizen
of the United States of America, residing in the
city of Providence, county of Providence, and
State of Rhode Island, have invented a new,
original, and ornamental Design for a Pin Clip,
of which the following is a specification, refer-
ence being had to the accompanying drawing,
forming part thereof.

Fig. 1 is a plan view of a pin clip showing my
new design.

Fig. 2 is an edge view thereof.

I claim:

The ornamental design for a pin clip, as shown.

GENE VERRECCHIO.
